UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A CAP OR COVER FOR TALCUM-POWDER BOXES.

53,442.

Specification for Design.

Patented June 17, 1919.

Application filed September 20, 1913. Serial No. 790,952. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Cap or Cover for Talcum-Powder Boxes, of which the following is a specification, reference being had to the accompanying drawing, forming part thereof.

Figure 1 is a plan view of a cap or cover for talcum powder boxes.

Fig. 2 is a side view.

Fig. 3 is a perspective view of the same.

I claim:

The ornamental design for a cap or cover for talcum powder boxes, as shown.

EDMUND HOFFMAN.
